AND C. H. GILLIG, OF SAN FRANCISCO, CALIFORNIA.

GOVERNOR OR VELOCITY REGULATOR.

Application filed April 24, 1924. Serial No. 708,815.

My invention relates to a governor, or velocity regulator for engines. It is especially adapted for regulating the speed of an internal combustion engine, such as is commonly used in automobiles and trucks, thereby regulating the speed of the vehicle of which the engine is a part. My device is not limited for use to automobile or internal combustion engines, as it can in a modified form be used on other engines.

The object I have accomplished is the construction of a governor to regulate automatically the speed of the engine by means of the velocity of the fluid or fuel being drawn into the chamber to move the piston. Other objects will be disclosed in the specification.

I accomplish these objects by means of the device described in the specifications and illustrated in the accompanying drawing, in which—

Fig. 1 is a vertical sectional view of a fuel supply pipe in which this regulator has been installed, and Fig. 2 is a view of the balanced valve in said pipe, the latter being shown in section.

Referring to the form of the invention shown in Figs. 1 and 2, it will be seen that 10 represents a tube having the elbow 18 at its upper end, through which the fuel passes to the combustion chamber of the engine when it is operating. The direction of the flow of the fuel is shown by arrow 11. Within tube 10 is pivoted a butterfly valve 4 adapted to close the opening through the tube. As shown in the drawing, this butterfly valve rotates on axis 5, and functions by means of a connecting rod 16 pivoted to a post 6, attached to the butterfly valve 4. I 40 have provided a baffle plate or piston 12 which fits loosely in pipe 10. This baffle plate is connected with a stem 8 which extends through the upper portion of the wall of the elbow of the intake manifold. On 45 the lower surface of the said piston is attached a nut 17 which is adapted to screw on a threaded rod 9, pivoted to connecting rod 16. As the nut 17 is approximately on the lateral diameter of pipe 10, I have bent 50 the lower portion 3 of rod 9 so it will cooperate with connecting rod 16 without conflict with the butterfly valve 4. A head 13 is attached to rod 8 for the purpose of adjusting the length of rod 9, this adjustment being possible by screwing to the left or to the

right the nut 17 on the threaded rod 9. A coil compression spring 7 normally holds piston baffle plate 12 in a downward position, holding the butterfly valve open. As the fuel is drawn through tube 10 the fuel 60 velocity will necessarily raise baffle plate 12 against a spring 7, said spring being weak and adapted to normally hold the piston in a downward position, or partially closed, depending on the velocity of the flowing fuel. 65 When the fuel velocity is released, the spring 7 normally pushes piston 12 downward, the downward movement being limited by stop 2, and such movement of the baffle plate will open butterfly 4, permitting more fuel to 70 pass through said intake pipe. The height to which baffle plate 12 can be raised depends upon the velocity of the flowing fuel or gas, and it is here noted that by shortening or lengthening rod 9, lesser or greater 75 fuel velocity will close butterfly valve 4. By this means an adjustment of nut 17 on rod 9 can regulate the maximum speed of the engine, and the regulator is ordinarily so adjusted that it will not work at all below a 80 certain speed.

It will be noted that in each of the designs, that the operative member 12 and 64 does not fill the passage way in which it is moved, and consequently it is moved against 85 the action of its corresponding spring only by variations in velocity of the fuel being moved, regardless of whether the absolute pressure in the fuel pipe is high or low; and both operative members are ordinarily so 90 adjusted that they are not affected by low velocity of the fuel passing to the explosion chamber.

This enables the engine to be operated with the maximum power at low speed, or at any 95 speed under the maximum set, but above which maximum the engine will not be permitted to go, and it is also to be seen that the balanced valve does not affect the movement of the operative member in any degree, nor does it in any way change its condition with respect to the fuel opening, with the result that it is possible to prevent the engine from exceeding a speed above a given maximum.

What I claim is as follows, but various modifications may be made in the construction shown in the drawings and above particularly described form, within the purview of my invention.

A regulating device for explosion engines, comprising in combination a fuel intake channel to the cylinder of the engine, a balanced butterfly valve in said channel, a flat movable plate adapted to rest on a seat in said channel, a rod fixed to said plate and extending through said channel wall, a slot in the outer end of said rod, a light spring adapted to normally hold said flat plate on its seat, a hub on said plate, screw threads in said hub, a threaded rod engaging the thread in said hub, and a pivoted rod connecting said threaded rod with said butterfly valve.

FRED C. MYER.
